United States Patent Office.

ALBERT M. DEXTER, OF PHILADELPHIA, PENNSYLVANIA, ASSIGNOR TO
ISAAC TOWNSEND, OF SAME PLACE.

Letters Patent No. 67,032, dated July 23, 1867.

IMPROVED BREAD-CUTTER.

The Schedule referred to in these Letters Patent and making part of the same.

TO ALL WHOM IT MAY CONCERN:

Be it known that I, ALBERT M. DEXTER, of Philadelphia, in the county of Philadelphia, in the State of Pennsylvania, have invented a new and useful Improvement on a Bread-Cutter; and I do hereby declare that the following is a full, clear, and exact description of the construction and operation of the same, reference being had to the annexed drawings, making a part of this specification, said drawings being all in perspective.

Figure 1 is a front view, K the knife of steel, F the frame of wood.

Figure 2 is a back view, lettered the same as fig. 1.

Figs. 1 and 2 are on a scale of about one-fourth a convenient size, the following being on a scale of about three-fourths a convenient size.

Figure 3 is the crank, H being the handle of wood, which is riveted to the iron part by a long rivet.

Figure 4 is the nut which holds the crank and knife on to the crank-shaft, seen at *n*, fig. 1.

Figure 5 is the gauge, S being the thumb-screw, by means of which it is fastened to the gauge-shaft, seen in fig. 6.

Figure 6 is the gauge-shaft.

Figure 7 is the crank-shaft, E being the eccentric, which oscillates the gauge-lever.

Figure 8 is the box holding back end of gauge-shaft.

Figure 9 is a spiral spring, which moves the gauge up, as seen at *u* in fig. 1.

Figure 10 forms the journal for the crank-shaft, seen at 10', fig. 2, also at 10', fig. 1.

Figure 11 is the front support, the hole at *x* being for the crank-shaft, and the hole at *y* for the gauge-shaft, while the "pin" is to hold the gauge-lever, allowing it to oscillate.

Figure 12 is the stop to keep the gauge-lever in place, being screwed to the underneath side of the frame.

Figure 13 is the gauge-lever, the teeth at T playing into the teeth at T in fig. 6.

Figure 14 is the back support, seen at 14' in figs. 1 and 2.

As a careful inspection of these drawings will enable any one skilled in the art to construct my improved bread-cutter, I will proceed to describe its operation.

The bread-cutter may be first fastened to the table or shelf near the edge, so as to allow the knife and crank to revolve. Then, having adjusted the gauge to the required thickness by means of the thumb-screw S, fig. 1, place the bread to be sliced into the frame F, fig. 1, letting it touch the gauge *u*. Hold it firmly, while with the other hand turn the crank forward, and the knife K will slice off the bread; and the eccentric E, fig. 2, acting on the gauge-lever, raises the end, seen at L, fig. 2, thus turning down the gauge *u*, and allowing the slice of bread to fall and the crank to pass the gauge, at which point the eccentric E on the crank-shaft, fig. 2, will have so far revolved as to let the action of the spiral spring S S, fig. 2, turn the gauge up again, as at *u*, fig. 1. Move the bread up to the gauge as before, and continue at will.

The operation of my bread-cutter is much better, besides being somewhat less expensive, by using a very thin knife, which may be done, since I rivet the crank firmly to the knife, seen at R, fig. 1, thus strengthening the knife and forming one new feature in my invention. The operation of the gauge, from its simplicity, is not liable to get out of order, and is just what is required to gauge the thickness of the bread slices.

What I claim as my invention, and desire to secure by Letters Patent, is—

1. A bread-cutter, the use of a gauge-lever, operated by the knife-shaft, in combination with the gauge-shaft, furnished with teeth meshing on the toothed segment of the lever.

2. The crank-handle C, riveted to the knife-handle at one end, and secured to the knife-shaft at the other, as and for the purpose herein specified.

ALBERT M. DEXTER.
